CONTROL CONSOLE FOR CAR WASHING APPARATUS

Kurt Moser, Vaterstetten, Germany, assignor to
Michael Bamberger, Munich, Germany

Filed Sept. 22, 1966, Ser. No. 3,956

Term of patent 3½ years

(Cl. D26—5)

FIG. 1

FIG. 2

FIG. 3

FIG. 4

FIG. 5

FIG. 6

FIG. 7

FIGURE 1 is a front perspective view of a new design for a control console for car washing apparatus;

FIGURE 2 is a front elevational view thereof;

FIGURE 3 is a rear view thereof;

FIGURE 4 is a top view thereof;

FIGURE 5 is a bottom view thereof;

FIGURE 6 is a side view thereof taken in the direction viewing the console from the left of FIGURE 1, and,

FIGURE 7 is a side view thereof viewing the console from the right of FIGURE 1.

The dominant portions of the design reside in the features shown by the solid lines.

I claim:

The ornamental design for a control console for car washing apparatus, substantially as shown and described.
